[57] ABSTRACT

In a preferred embodiment, there is a ski having three

6 Claims, 13 Drawing Figures

This diagram illustrates an exploded view of a gun barrel assembly. The main components shown are:

- 2: A handle or grip located at the top left and top right.
- 6: A sight or aiming device located at the top center.
- 14: A front sight or similar component on the left side.
- 15: A rear sight or similar component on the left side.
- 9: A barrel or main body.
- 21: A base or mounting plate.
- 21a: A part of the base.
- 22: A mounting plate or base.
- 22a: A part of the base.
- 22aa: A part of the base.
- 17a: A pin or fastener.
- 17b: A pin or fastener.
- 23: A pin or fastener.
- 17c: A pin or fastener.
- 10: A base or mounting plate.
- 11: A base or mounting plate.
- 7: A base or mounting plate.
- 18a: A base or mounting plate.
- 18b: A base or mounting plate.
- 16a: A pin or fastener.
- 16b: A pin or fastener.
- 16c: A pin or fastener.
- 12: A base or mounting plate.
- 13: A base or mounting plate.
- 8: A base or mounting plate.

The diagram shows the disassembled parts of the gun barrel assembly, with arrows indicating the direction of assembly.

sections from front to back axially along the elongated ski, each of the front section and rearward section being pivotable upwardly from the central section opposite ends on respective hinges and with each pivotal portion including a spring biasing the respective end section into a position axially aligned with the central portion and being pivotal of the end portions only upon excessive pressure pressing upwardly against the bottom face of the particular end portion, such as when an amateur skier falls either backwardly or forwardly, the permissive pivotal action serving possibly to avoid major leg and/or ankle injuries to such an unskilled skier, the pivoting of the end portion(s) under such circumstances avoiding undue pressure(s) on the limb(s) of the skier during the fall, but the biasing pressure of the spring(s) being sufficient to avoid the pivoting of the end portion(s) during normal skiing by such a person.

SAFETY SKI

The present invention relates to ski particularly adapted for safe use for recreation by the inexperienced skier, or learner.

BACKGROUND TO THE INVENTION

Prior to the present invention little if any attention has been given to the problems facing the middle age person who wishes to participate in the sport of skiing as well as any other person who because of the time and/or cost factors cannot avail himself of sufficient skiing practice and experience to become a polished skier but who nevertheless would like to participate in the sport without the possibility of breaking himself up while having a little fun and a few skiing thrills of a mild nature. With the skis of the type accepted as conventional, it is very likely that such person(s) often will end up with their ankle(s) and/or knee(s) in casts, hardly a luxury that most part-time skiers can afford, as well as the fact that such injuries can often result in permanent crippling or at least lasting effects of such injuries throughout the remainder of their respective lives. All of this, or at least a good part thereof is due to the awkwardness of the unpracticed inexperienced person together with the fact of bones becoming more brittle normally in later years, as well as persons in later years after youth becoming generally less agile. The conventional ski does not bend during a fall, it being normally the person's joint that that becomes twisted out of the socket or the bone broken, normally because of incorrectly falling, but which incorrect falling normally is not correctable in the light of the little time allotted to the sport as well as the fact that unless a person begins skiing at an early age in life, there is little likelihood that he will ever readily develop even the basic skiing skill normally necessary to avoid injury with the conventional ski.

THE INVENTION

Accordingly, an object of the present invention is to avoid problems of the type and nature discussed above at least to a major extent.

Another object is to make possible a fall during the wearing of skis, even with incorrect falls, without any significant possibility of injury to the person during the fall, when skiing.

Accordingly, the above one or more objects are made possible by another object which is to obtain a novel ski which avoids the prior difficulties.

Another object is to obtain the preceding objects at a low cost of manufacture and low cost of materials, thereby making available such safety ski to the general thrifty public that cannot afford higher costs.

Other objects become apparent from the preceding and following disclosure.

One or more of the preceding objects are obtained by the invention as defined herein.

Broadly the invention includes a ski, obviously normally employed in pairs thereof one for each foot, in which the ski includes at least a rearward portion typically starting right behind the ski-boot mount which is pivotable upwardly relative to a horizontal mid-portion on which the ski boot is mounted, such that if a skier falls backwardly, the rearward pivotable portion can remain substantially horizontal on the ground while the mid-portion pivots upwardly relative thereto allowing the skier to fall backward in a normal manner without

2

all of the stress being on the bending of the knees. In like manner the invention includes alternatively a forward portion alone or in combination with the rearward pivotal portion, the forward portion being similarly pivotally joined to the central boot-mounting portion such that the skier may fall forward with the aft portions of the ski coming up with the heel of the boot while the forward portion remains about horizontal, thus avoiding undue stress of the knees and ankles in 10 a direction that these joints cannot bend. In each embodiment or combination thereof, at the pivot point there is a spring preferably of the leaf type, but permissively also of coil type spring(s), connected to opposing adjacent ends such to normally sustain and/or hold the 15 adjoining ski parts in axially aligned linear positions relative to each other and to biasingly oppose any tendency toward the pivoting thereof, and totally avoiding pivotal motion is a downwardly direction of an end portion relative to the boot-mounting portion. In a preferred embodiment of the invention, there is easily inserted alternate leaf spring(s) to reduce or increase the biasing resistance to pivotal motion, as dependent upon the weight and general size of the particular skier to be using the spring. Clearly, a light person would require 20 less biasing tension than a heavy person, because if a light person were to fall it would be desirable for the biasing spring to be sufficiently weak as to permit the end pivotal portion to pivot to thereby avoid leg and/or ankle injury. Similarly for a heavy person, stronger 25 springs would be desireable within reason; it should be noted however, that even a heavy person needs to have sufficiently weak springs as to avoid undue stress on his 30 ankles and knees if he should fall. At the same time, for either light or heavy persons, in order for the skies to 35 be functional for normal recreational skiing use, it is essential for the spring to be sufficiently strong as to normally maintain the ski in the straight or linear state during normal skiing exercises or use thereof, although there is some additional benefit gained from the skis of 40 the invention during skiing on a less-than-smooth terrain in that as lumps and or bumps are encountered beyond what might be normally tolerated and handled successfully by an inexperienced skier, the permissive flexing of the end of the ski—as the front of the ski pivoting upwardly and on the reflex straightening immediately thereafter serving to lift the central portion over the bump, the pivotal biased portion serves in effect as a shock absorber during the skiing. It is to be understood that there are many other advantages to be associated with such a safety ski, and that it is the purpose of 45 this disclosure to merely present basic embodiments and some primary benefits thereof.

THE FIGURES

55 FIG. 1 illustrates an elevation side view of a typical ski of the present invention, this embodiment having both forward and rearward pivotal end portions.

FIG. 2 illustrates an elevation plan view of the embodiment as taken along lines 2—2 of FIG. 1.

60 FIG. 3 illustrates a cross-sectional view as taken along lines 3—3 of FIG. 2.

FIG. 4A illustrates an alternative embodiment utilizing a coil spring, illustrated in in-part view in an elevation plan view.

65 FIG. 4B illustrates an in-part view in a side view of the FIG. 4A embodiment as taken along lines 4B—4B of FIG. 4A.

FIG. 5 illustrates a cross-sectional view as taken along line 5—5 of FIG. 2.

FIGS. 6—10 illustrate additional alternate embodiments.

In greater detail, FIGS. 1 through 3 and 5 disclose one typical embodiment embodying various preferred features, and the FIGS. 4A and 4B illustrate an alternate embodiment. In the FIGS. 1—3 and 5 illustrate a safety ski 6 having a central portion 7 and a forward portion 8 and a rearward portion 9, with respective upper and lower faces 10 and 11, 12 and 13, and 14 and 15 thereof. The front portion 8 is pivotably joined with the central portion 7 by a combination hinge-spring biasing means including mounted on the upper face 12 the pin-holding element 16a secured by brads such as 16e and 16ee with a central aperture therein through which leaf spring 16b extends and is anchored by brads 16d and 16d'. Similarly the central member 7 is pivotably attached and biased axially by element 17a, pin 17c locking the leaf-spring 17b into its position, and there being corresponding brads 17d and e and the like. Boot-heel mount and boot-toe mount 18a and 18b respectively are mounted on the upper face 10 of portion 7. The bottom face 15 is recessed at its forward portion 21 to define a space 21a, and the portion 21 overlaps and lies on top of the rear portion 22 of portion 7, with a recess-space 22a having an upright-step wall 22aa receivable of the downward-step projection 23 such that the projection 23 in effect locks into the step-recess 22a. The recess 21a and corresponding forward recess 21a' each serves to prevent snow from becoming packed within the space such that would serve to prevent the pivotal portion when pivoted (as during a fall) from not thereafter fully fulling straightening-out axially-linearly.

The FIGS. 4A and 4B disclose an embodiment utilizing a more conventional hinge together with a coil spring, including the hinge legs 24a and 24b of one element mounted on one portion, and 26a and 26b legs of another hinge element mounted on the other ski portion, fastener together with pin 25 around which also is centrally mounted the coil spring 19 with one end mounted on one portion by post 20b and the other end 19a mounted on post 20a.

FIGS. 6, 6A, 7, and 8 illustrate an alternate embodiment and FIGS. 8A, 9 and 10 illustrate variations thereon, the Figures all being in-part views, the FIGS. 6, 6A, and 9 being elevation side view, and FIGS. 8 & 8A being a side cross-sectional views and FIGS. 7 and 10 being elevation plan views. FIG. 6A is a variation on FIG. 6.

FIG. 6 and 6A illustrate forward section(s) 7'/7a' and rearward portion(s) 9'/9a' mounted respectively on hinge flanges (the same in both Figures) 11a' and 11b' pin-pivoted at 24', with bolt-nuts 29/29a and 32/32a mounted on securing bolts such as 29/29a securable of one leaf-spring 27 or multiple-pancaked leaf-springs 27a, 27b, and 27c in a position spaced above and away from the top surface of the ski portions, there being a slot 34/34' in the one or more leaf-springs in which the bolts 29/29a are inserted and whereby upon the bending at pivot points 24' the leaf-springs(s) are axially slidably transversely of the bolt axis by virtue of the slot(s) thereby allowing the pivotal action at 24'; the elevated leaf-springs by being elevated serve to place the bending-flexing stress substantially evenly along the entire length of each leaf-spring,

rather than at the pin-point solely as is the case in the FIG. 1 embodiment.

FIGS. 9 and 10 differ from FIGS. 6, 7, and 8 only in the advantageous side-flanges 37 making for less snow collection and better sliding of the ski when slanted onto its edge, and the hinge pivot point 24'' is more forwardly located for greater leverage.

It is to be understood that it is within the spirit and scope of the present invention to make such variations and modifications and substitutions of equivalents as would be apparent to a person of ordinary skill.

I claim:

1. A safety ski device comprising in combination: a substantially flat-bottomed ski strip elongated along its forward-to-rearward axis and divided into a least a main portion and a rearward trailing portion, the main portion including boot-mount means for mounting on a top face of the ski strip a boot element by which a skier may foot-mount the ski strip, hinge means pivotably mounting the rearward trailing portion, and biasing leaf-spring means including (a) mounting-structure projections projecting a predetermined distance from upper faces of each of the main portion and the rearward trailing portion to points located spaced-above said upper faces and (b) at least one leaf spring fixedly mounted at one end of its elongated axis and slidably mounted at an opposite end of its elongated axis onto and extending between said projections of the main portion and of the rearward trailing portions respectively, said main portion and said rearwardly trailing portion being axially aligned with one-another, the rearward trailing portion being pivotable upwardly from the hinge means, the leaf-spring means exerting a predetermined degree of biasing pressure and being mounted such that biasing stress is applied to each of the main portion and the rearward trailing portion respectively, biasing the rearward trailing portion into a normally about axially aligned position, said pivotable and biased rearwardly trailing portion being responsive pivotable to predetermined degrees in number dependent upon the amount of excessive upwardly directed pressure applied to a bottom face of the rearwardly trailing portion.

2. A safety ski device of claim 1, in which at a junction point at a rearward end of said main portion and at a forward end of said rearwardly trailing portion, one of the rearward end and the forward end overlaps the other.

3. A safety ski device of claim 2, in which one of the overlapping ends includes an upright projection and the other overlapping end defines an upright receptacle matably receivable of the projection lockable of the main portion and the rearwardly trailing portion against axial disengagement and axial displacement of one relative to the other.

4. A safety ski device of claim 3, in which the overlapping end of the rearward trailing portion is above the overlapping end of the main portion, and the trailing edge of the overlapping end of the main portion being recessed upwardly from its bottom flat face.

5. A safety ski device of claim 4, in which said main portion includes a forward second hinge means mounted at a forward end of the main portion, and the device further including a forward flat-bottomed ski-strip portion axially aligned with the main portion; a rearward end of the forward portion being mounted upwardly-pivotably on said forward second hinge

means, the forward second hinge means including a second spring means mounted relative to the rearward end of the forward ski-strip portion such that the forward ski-strip portion is biased downwardly into a position normally axially aligned with the main portion under a predetermined stress against pivotal motion upwardly, the forward ski-strip portion being upwardly pivotable responsive to predetermined amounts of excessive pressure on the under face of the forward ski-strip portion.

6. A safety ski device of claim 1, in which said main portion includes a forward second hinge means mounted at a forward end of the main portion, and the device further including a forward flat-bottomed ski-

strip portion axially aligned with the main portion, a rearward end of the forward portion being mounted upwardly-pivotably on said forward second hinge means, the forward second hinge means including a second spring means mounted relative to the rearward end of the forward ski-strip portion such that the forward ski-strip portion is biased downwardly into a portion normally axially aligned with the main portion under a predetermined stress against pivotal motion upwardly, the forward ski-strip portion being upwardly pivotable responsive to predetermined amounts of excessive pressure on the under face of the forward ski-strip portion.
